United States Patent Office.

QUIMBY S. BACKUS, OF WINCHEON, MASSACHUSETTS.

Letters Patent No. 82,583, dated September 29, 1868.

IMPROVED CHUCK-DRILL.

The Schedule referred to in these Letters Patent and making part of the same.

TO ALL WHOM IT MAY CONCERN:

Be it known that I, QUIMBY S. BACKUS, of Winchendon, in the county of Worcester, and State of Massachusetts, have invented certain Improvements in Chuck-Drills, of which the following is a full, clear, and exact description, reference being had to the accompanying drawings, making part of this specification, in which—

Figure 1 is a perspective view of my improved drill.

Figure 2 is a longitudinal section through the centre of the same.

Figure 3 is a transverse section on the line $z z$ of figs. 1 and 2.

Figure 4 represents the point or end of the drill, in elevation.

My invention relates to that class of drills, ordinarily termed "chuck-drills," in which the drill, without revolving, is fed forward into the work, which latter simply revolves without advancing; and my invention consists in a drill, having each of two of its opposite sides provided with a groove, which inclines down to its point, to allow the oil to flow thereto, and affords an unobstructed passage for the chips or shavings to pass out, or the grooves may be straight and not inclined, while the other two opposite sides of the drill are curved, and of uniform diameter throughout their length, the cutting-edges produced by the intersection of the grooves with the two opposite sides being so curved as to form a peculiar-shaped "lip," which, after entering the work, requires but slight power to press it forward, by which construction I am enabled to bore a true hole centrally into the work, with the utmost facility—an operation heretofore extremely difficult to accomplish with drills of other forms.

To enable others skilled in the art to understand and use my invention, I will proceed to describe the manner in which I have carried it out.

In the said drawings, A represents my improved chuck-drill, with each of two of its opposite sides provided with a groove, a , which inclines from near the back of the drill at 5 to the "point" 6, in order to allow the lubricating-material to flow down thereto, and forms a channel, by which the chips are free to pass out of the hole being bored in the work. The other two opposite sides or surfaces b are curved outward in transverse section, the degree of curvature corresponding to the circumference of the hole of the size to be bored.

The diameter or width of the drill between the sides b is the same throughout its length, excepting from its point 6 to the intersections of these sides with the grooves a , which thus form the cutting-edges c , the curvature of which is such that after they enter the revolving work, while being bored, the body of the drill is advanced rapidly, and with the expenditure of but little power, forming for itself a snug bearing against the side or periphery of the hole, which thus prevents it from having any lateral play therein; the form and relation of the grooves a and sides b also serving to stiffen and strengthen the drill, and prevent it from springing while advancing.

The inclination of each of the cutting-edges c from 6 to 7 is about forty-five degrees, and the peculiar shape of the "lip" thus formed, admits of its being conveniently sharpened.

By thus making the drill, throughout its length, of the same diameter between its two opposite sides b , a hole bored by it is made perfectly true, and in a line with the exact centre or axis of the article being bored, and the drill is worn away uniformly, so as to admit of its being used when quite short, as well as when of its original length.

Claim.

What I claim as my invention, and desire to secure by Letters Patent, is—
The within-described "chuck-drill," constructed to operate substantially as set forth.
